Harry Raddon Greene, Pasadena, Calif., assignor to R. A. Fischer & Co., Glendale, Calif., a partnership

Application January 2, 1953, Serial No. 22,986

Term of patent 14 years

(Cl. D83—1)

To all whom it may concern:

Be it known that I, Harry R. Greene, a citizen of the United States of America, residing at Pasadena, in the county of Los Angeles and State of California, have invented a new, original and ornamental Design for a Vibrator, of which the following is a specification, reference being had to the accompanying drawings forming a part thereof:

I claim:

The ornamental design for a vibrator, as shown.

HARRY RADDON GREENE.
